[57] ABSTRACT

A film cartridge comprising two winding drums is attachable to a reeling device selectively in a normal position, a side-for-side inverted position, an end-for-end inverted position and in a side-for-side, end-for-end inverted position. In any selected attached position of the cartridge the winding drums are drivingly connected to drive assemblies of the reeling device by coupling means. The drive assemblies and the coupling means are such that one of the winding drums can be rotated by the respective drive assembly in a first direction and the other winding drum can be rotated by the other drive assembly only in a direction opposite to said first direction.

REELING DEVICE FOR INFORMATION CARRIER FILM

BACKGROUND OF THE INVENTION

The invention relates to a reeling device for winding, stopping and rewinding a flexible information carrier or film such as is used in photographic type setting machines or in apparatus of a similar nature.

The invention is concerned more particularly with the problem of controlling the winding, stopping and rewinding of a flexible information carrier quickly and reliably in such a manner that a certain portion of the carrier, that is, a specific piece of information can be scanned and made individually available for subsequent use. In photographic type setting machines, for instance, the information carrier for the various letters and other symbols to be printed is customarily provided in the form of a spool of negative film which has all the needed letters and symbols distributed over its length. In order to utilize such a machine to its fullest possible extent it is not only necessary to advance, stop and reverse the film quickly and reliably as needed, but it should also be possible to present the film to a scanning head, which usually incorporates a suitable optical system, in such a manner that the information thereon will appear either in a normal upright position, or in an upside down position, or in an end for end inverted position or in an upside down and end for end inverted position.

SUMMARY OF THE INVENTION

The invention provides a device for reeling a flexible information carrier back and forth between a pair of winding drums and which is operable not only to start, stop and reverse the rotation of the drums so as to wind any desired length of the carrier upon one drum or the other and to hold any portion of the carrier at standstill between the drums, but which is also operable to present the information of the carrier selectively in either a normal upright position or in an upside down position, or in an end for end inverted position, or in an upside down and end for end inverted position.

More specifically, the invention provides a reeling device of the above outlined character which requires no change or adjustment of the driving mechanism for the winding drums in order to present carrier information in any of the four mentioned positions.

The invention further provides a reeling device of the above outlined character which is mechanically simple, efficient and reliable in operation and which may be manufactured at relatively low costs.

In accordance with the invention, a reeling device of the above outlined character is provided with one drive assembly for one of the winding drums and with another drive assembly for the other winding drum, each drive assembly comprising a pair of relatively rotatable driving members connected in drive reversing relation to each other, and each having a coupling element for cooperative engagement with either of the winding drums, the arrangement being such that when one drum is coupled to one or the other driving member of one drive assembly, the other drum is uncoupled from the corresponding driving member of the other drive assembly, and so that, conversely, when the other drum is coupled to one or the other of the driving members of the other drive assembly, the one drum is uncoupled

from the corresponding driving element of the one drive assembly.

The winding drums and the torque transmitting elements are operatively interrelated according to the invention, in such a manner that one of two driving members which is rotatable in a first direction can be operatively connected with the one winding drum while the other of the two driving members which is operatively effective in the other direction can be connected in an operative manner to the other winding drum. On the other hand, since the two pairs of driving members are each connected with a common drive shaft via one-way clutches by means of which only one pair of the driving members is driven, depending on the direction of rotation of the common drive shaft, it follows that according to the selected direction of rotation of the common drive shaft only one of the winding drums is driven by the driving member coaxing therewith while the other drum can turn freely, since the driving member in cooperative relation therewith is separated from the common drive shaft via the associated one-way clutch and can thus turn freely as well. If, on the other hand, the direction of rotation of the common drive shaft is reversed, then the other winding drum is rotated in the other direction by its associated driving member which is now coupled with the common shaft while the previously driven driving member can rotate freely together with its associated winding drum. In this way, both forward and backward movement of the information carrier is possible in very rapid succession solely by changing the direction of rotation of the common drive shaft without having to engage or disengage the driving members with or from their associated winding drums.

In actual practice, it is particularly advantageous when, in accordance with a further feature of the invention, the winding drums can be selectively connected with the two pairs of driving members of the reeling device so that the information carrier can be both advanced and reversed in a normal, reversed, inverted-reversed or inverted position by operation of the reeling device without changing the winding relation between the information carrier and the winding drums. According to this feature of the invention, the opposite ends of the winding drums are connectable, respectively, with the two driving member pairs in various positions, thereby permitting the information carrier to be advanced and reversed in various positions of presentation to a scanning system, depending on the positioning of the winding drum relative to the driving members of the reeling device.

In accordance with a further feature of the invention, the winding drums and the information carrier are accommodated in a cartridge which can be positioned on the reeling device in four different positions of attachment thereto, each establishing a driving connection between one winding drum and one of a pair of driving members, and, at the same time, establishing a driving connection between the other winding drum and one of the other pair of driving members. In such an assembly according to the invention, therefore, both the position of the information carrier with respect to a scanning system and the correct arrangement of the forward and backward drive is determined solely by placing the cartridge in one of its four possible positions relative to the reeling device.

In accordance with a preferred embodiment of the invention, the reeling device comprises a pair of oppo-

sitely rotatable driving members for one of the winding drums, another pair of oppositely rotatable driving members for the other winding drum, and two bevel gear assemblies, one operatively associated with one of said pairs of driving members, and the other operatively associated with the other of said pairs of driving members. Each bevel gear assembly comprises first and second bevel gears connected, respectively, to the associated drum driving members, and a third bevel gear in mesh with the first and second bevel gears. Alternately engageable clutches connect the third bevel gears, respectively, with a common, reversibly rotatable drive shaft. By transmitting driving torque in this manner from a third bevel gear to first and second bevel gears which are in mesh therewith, rotation of the first and second bevel gears in opposite directions is achieved so that these merely need to be connected with the two driving members of a driving pair in a suitable manner to ensure that these two driving members will also rotate in the respective opposite directions.

This is achieved in accordance with the invention, for example, in that the one respective driving member is a first disc provided with a pin, said disc having a central recess which receives a second disc designed as the other driving member and also provided with a pin and in that the second disc is connected via a shaft to the second bevel gear which passes through a hollow shaft connecting the first disc with the first bevel gear.

The connection between the winding drums and the respectively associated pairs of driving members of the reeling device is achieved in accordance with a further feature of the invention by providing each winding drum at one end with a radially outer coupling recess and with a radially inner idling recess, and at its other end with a radially outer idling recess and with a radially inner coupling recess, so that positioning of the winding drums on the reeling device in end for end inverted relation to each other will connect the radially outer coupling recess and the radially inner idling recess of one drum in driving and non-driving relation, respectively, with one pair of said driving members, and so that at the same time the radially inner coupling recess and the radially outer idling recess of the other drum will be connected in driving and non-driving relation, respectively, with the other pair of driving members.

With the aid of this very simple mechanical construction, the exactly correct relationship between the driving members of the reeling device and the film winding drums is achieved by merely placing the drums together with the cartridge into an operative position on the discs or pins of the driving members.

According to a further feature of the invention, the common drive shaft is connected with the third bevel gears via one-way clutches at the opposite ends thereof, the clutches acting in opposite directions of rotation. This clutch arrangement ensures that, depending on the direction of rotation of the common drive shaft, only one of the two pairs of driving members will be driven and the other pair of driving members can turn freely relative to each other and relative to the common drive shaft.

In a preferred embodiment of the invention, the one-way clutches are of the wrap-around drag spring type. These wrap-around spring type clutches each comprises, in accordance with a further feature of the invention, a coil spring mounted on the shaft with pre-

bias, one end of said spring engaging positively a sleeve surrounding said shaft, and brake springs are provided with exert a force on at least one part of the outer peripheral surface of said sleeve and whose braking torque is greater than the torques of the bearing friction and the lifting torque of the coil spring.

A very rapid transport movement of the information carrier is possible both in a forward as well as in a reverse direction with the aid of these one-way clutches of relatively simple design and with the aid of the brake springs acting on the sleeves; moreover, the information carrier can be stopped between both movements at any desired place in a reliable and positively controlled manner.

DRAWINGS

The invention will now be more fully explained with reference to the embodiment illustrated in the drawings, in which:

FIG. 1 shows schematically an information carrier film in normal position presenting a series of characters thereon in an upright position;

FIG. 2 shows the information carrier film in a position presenting the series of characters in an upside down, end for end inverted position;

FIG. 3 shows the information carrier film in a position presenting the series of characters in an upside down position;

FIG. 4 shows the information carrier film in a position presenting the series of characters in an end for end inverted position;

FIG. 5 is a sectional view of a reeling device for a film cartridge shown in FIGS. 7 and 8;

FIG. 6 is a schematic end view of a one-way clutch incorporated in the device shown in FIG. 5;

FIG. 7 is a sectional elevation of a film cartridge for use with the reeling device shown in FIG. 5; and

FIG. 8 shows the cartridge of FIG. 7 in an elevation of the front ends of the winding drums.

DETAILED DESCRIPTION

In FIGS. 1 to 4, the possibilities of driving an information carrier 100 with the winding drums 32 and 33 is schematically illustrated; according to whether movement of the information carrier 100 toward the left or right end of the figure is desired, the winding drums 32 and 33 must not only be rotated in one direction or the other, but also one winding drum must be driven while the other winding drum turns freely and vice-versa. There is a total of four different basic functions of each winding drum for the different positions of the information carrier illustrated in FIGS. 1 to 4 and its transport directions, namely: for each driving side cooperating, driven clockwise, freely turning clockwise, driven anticlockwise and freely turning anticlockwise.

These four basic functions may be performed in a very simple constructional manner by means of the driving system incorporating the invention as illustrated in FIG. 5 and the correspondingly designed winding drums.

There is provided in FIG. 5 a common drive shaft 1 which is rotatable in opposite directions by means not illustrated here in detail, and which may be motor driven or manually operated. The drive shaft 1 is connected with bevel gears 4 and 5 via one-way clutches 2 and 3, respectively, which operate to transmit torque

in relatively opposite directions. The bevel gear 4 meshes with companion bevel gears 6 and 8 which are disposed coaxially at right angles to the axis of the bevel gear 4, and the bevel gear 5 similarly meshes with companion bevel gears 7 and 9. Bevel gears 6 and 7 are journaled in a manner which is only schematically indicated in the drawing and are connected with first discs 12 and 13 via hollow shafts 10 and 11. Discs 12 and 13 have coupling pins 14 and 15, respectively, extending perpendicularly to the disc surface, as well as central recesses 16 and 17, respectively, in which other discs 18 and 19 are rotatably journaled in a manner not illustrated in detail. The discs 18 and 19 are provided with pins 20 and 21, respectively, which extend perpendicularly to the disc surface and are connected with the lower bevel gears 8 and 9, respectively, via shafts 22 and 23 which pass through the hollow shafts 10 and 11 and are rotatably journaled relative thereto; the shafts 22 and 23 are also journaled in a manner which is not illustrated in the drawings in detail.

The one-way clutches 2 and 3 have the same construction in principle, the clutch 2 however transmitting torque of the drive shaft 1 to the bevel gear 4 only in one direction and the clutch 3 transmitting torque of the drive shaft 1 to the bevel gear 5 only in the other direction. The bevel gears 4 and 5 are separated from the common shaft 1 similar to a free-wheeling arrangement for the opposite directions of rotation. The structure and mode of operation of the one-way clutches is explained hereinafter only with reference to the clutch 2, since the clutch 3 has the same structure in principle. There is mounted on a member 24 of the common shaft 1 as well as on a shaft member 25 of the bevel gear 4 in clearance fit a wrap around drag spring 26 which is covered by a sleeve 27 which surrounds the spring 26, the common shaft 1 and the shaft member 25 of bevel gear 4. Brake springs 28 and 29 act on one portion of the outer surface of the sleeve 27 as can be seen in FIG. 6. It can also be seen in FIG. 6 that one end 30 of the spring 26 is secured in a recess 31 of the sleeve 27.

The operation of such a wrap-around spring coupling is as follows. When the wrap-around spring coupling is acted upon in its direction of free rotation, the sleeve 27 is held fast by the brake springs 28 and 29 so that the spring is raised both from the shaft 1 and from the shaft member 25 of the bevel gear 4 when the common shaft 1 rotates contrary to the sense of winding of the tension spring thereby permitting free and almost frictionless relative movement between the bevel gear 4 and shaft 1. If the drive shaft 1 rotates in the sense of winding of the spring, however, the spring is contracted and is pressed against the shaft extension and shaft member 25 of bevel gear 4 while at the same time causing the sleeve 27 to rotate so that the bevel gear 4 is connected with the drive shaft 1 in a manner practically free of slip.

In the case of a first direction of rotation of the drive shaft 1, the torque of the drive shaft 1 is thus transferred via the bevel gear 4 to the bevel gears 6 and 8 which rotate in relatively opposite directions by virtue of their geometrical arrangement relative to the bevel gear 4. Since the discs 12 and 18 are rigidly connected with the associated bevel gears 6 and 8, discs 12 and 18 also rotate in relatively opposite directions. While torque is being transmitted to bevel gear 4, bevel gear 5 is simultaneously uncoupled from the drive shaft 1 so that bevel gears 7 and 9 are not driven and can thus

turn freely in relatively opposite directions due to the free-wheeling effect of the clutches. Torque applied by discs 13 and 19 to the associated bevel gears 7 and 9 can thus be absorbed without impediment due to the free rotation of bevel gear 5.

A cartridge 34 supporting winding drums 32 and 33 is schematically illustrated in FIGS. 7 and 8 without the information carrier which is also disposed in the cartridge and which can be wound back and forth between 10 winding drums 32 and 33. At its axial front end, the winding drum 32 has an annular recess 36 in which the coupling pin 14 can freely circulate when the cartridge 34 is placed in its FIG. 7 position on the reeling discs shown in FIG. 5. Winding drum 32 also has at its axial 15 front end recesses 38 which are designed in the shape of bores distributed over an inner pitch circle and which can be positively engaged by coupling pin 20 of disc 18 when the cartridge 34 is placed in its FIG. 7 position on the reeling device shown in FIG. 5. At its axial 20 rear end, winding drum 32 has bores 40 lying on a first larger pitch circle, which are positively engageable by coupling pin 14 of disc 12 when the cartridge 34 is inverted side for side from its FIG. 7 position. In addition, the rear end of the winding drum 32 also has a circular 25 recess 42 within which pin 20 of disc 18 can turn freely when the cartridge 34 is inverted side for side from its FIG. 7 position.

Similarly, the axial rear end of the winding drum 33 is provided with an annular recess 37 for free turning 30 of coupling pin 15 therein, and with bores 39 for positive engagement of coupling pin 21 when the cartridge is inverted side for side from its FIG. 7 position at its front end the winding drum 33 has bores 41 for positive 35 engagement with coupling pin 15, and a circular recess 43 for free turning of pin 21 when the cartridge is placed in its FIG. 7 position on the reeling device of FIG. 5. The winding drums 32 and 33 are disposed in the cartridge 34 so that heterologous ends of the winding drums which have differing designs with respect to 40 the bores and recesses are disposed at the opposite sides of the cartridge and the latter can be positioned on the reeling device shown in FIG. 5 either in the FIG. 7 position, or in its side for side inverted position, or in its end for end inverted position, or in its side for side and end for end inverted position.

It can be easily seen that when positioning the cartridge 34 in its FIG. 7 position on the reeling device shown in FIG. 5, the coupling pin 20 connected to disc 18 engages positively in a bore 38 while coupling pin 14 of disc 12 is capable of circulating freely in recess 36. At the same time, coupling pin 15 is positively connected with winding drum 33 while coupling pin 21 can turn freely in recess 43 when the cartridge 34 is connected in its FIG. 7 position with the device shown in FIG. 5. According to the directions of rotation (explained with reference to FIG. 5) of the driving members which are designed as discs 12 and 18, winding drum 32 is rotated in a first direction by means of coupling pin 20 and bevel gear 8 when clutch 2 takes effect while the driving member represented by disc 12 and turning in the opposite direction does not affect the winding drum 32. Since bevel gears 5, 7 and 9 are separated from drive shaft 1 via clutch 3 when the device in accordance with the invention is operated in the assumed way, it is possible for the driving member 13 which is operatively connected with the winding drum 33 by the coupling pin 15 to rotate freely so that wind-

ing drum 33 is capable of rotating freely in the same direction in which the winding drum 32 is driven. If the direction of rotation of the drive shaft 1 is reversed, however, the winding drum 33 is rotated in the other direction by the driving member 13 which is coupled to this winding drum by the coupling pin 15; at the same time, bevel gears 4, 6 and 8 are released through clutch 2 so that the driving member 18 which is positively connected with the winding drum 32 can freely rotate in the same direction as the winding drum 33. Since the pattern of the heterologous ends of the winding drums 32 and 33 at the rear side of the cartridge 34 is a mirror image of the pattern of the heterologous ends of the winding drums at the front side of the cartridge, exactly the opposite conditions are produced when the cartridge is inverted side for side from its FIG. 7 position without inverting the cartridge end for end from its FIG. 7 position.

Since the cartridge 34, however, can be positioned on the device shown in FIG. 5 not only with one or the other of its sides directed toward the driving members of the reeling device, but can also have its ends inverted by turning it about its axis of symmetry which lies parallel to the axes of rotation of the winding drums, the four various basic functions which were discussed hereinbefore can also be easily performed with the drive means illustrated in FIG. 5.

If the braking torque of the brake springs 28 and 29 acting on the sleeve 27 is greater than the torques of the bearing friction as well as of the lifting torque of the drag spring 26, then an immediate reversal of the direction of transport of the information carrier is also possible when the direction of rotation of the drive shaft 1 is reversed, that is, an immediate stoppage of the information carrier occurs when the drive shaft 1 is stopped.

In summary, the herein disclosed film cartridge has a pair of rotatable film winding drums 32, 33 at a fixed center spacing from each other, each drum being provided with torque transmitting coupling means at its opposite ends as shown at 38 and 40 for the drum 32, and at 39 and 41 for the drum 33. The herein disclosed reeling device comprises a pair of rotary drive assemblies 12, 18 and 13, 17 at the same center spacing from each other as the winding drums, the drive assemblies being detachably connectable with the coupling means of the winding drums. A pair of one-way clutches 2 and 3 are operatively interposed between a reversibly rotatable drive shaft 1 and the drive assemblies so that rotation of the drive shaft in one direction will be transmitted through one of the clutches to one of the drive assemblies, and so that rotation of the drive shaft in the opposite direction will be transmitted through the other clutch to the other drive assembly.

I claim:

1. The combination of a film cartridge having a pair of rotatable film winding drums at a fixed center spacing from each other; and a reeling device cooperable with said winding drums so as to wind a length of film back and forth therebetween; said winding drums each having torque transmitting coupling means at its opposite ends, and said reeling device comprising, a pair of rotary drive assemblies at the same center spacing from each other as said winding drums and detachably connectable, respectively, with said coupling means of said winding drums the winding drums can be rotated by the respective drive assembly only in a first direction and

the other winding drum can be rotated by the other drive assembly only in a direction opposite to said first, a reversibly rotatable drive shaft, and a pair of one-way clutches operatively interposed between said drive shaft and said drive assemblies so that rotation of said drive shaft in one direction will be transmitted through one of said clutches to one of said drive assemblies and so that rotation of said drive shaft in the opposite direction will be transmitted through the other of said clutches to the other of said drive assemblies.

2. The combination of a film cartridge having a pair of rotatable film winding drums; and a reeling device cooperable with said winding drums so as to wind a length of film back and forth therebetween; said winding drums each having torque transmitting coupling means at its opposite ends, and said reeling device comprising, a first pair of driving members interconnected for relative rotation in opposite directions and each having a coupling element releasably connectable with said coupling means of said winding drums; a second pair of driving members interconnected for relative rotation in opposite directions and each having a coupling element detachably connectable with said coupling means of said winding drums; a reversibly rotatable drive shaft; and a pair of one-way clutches operatively interposed between said drive shaft and said first and second pairs of driving members so that rotation of said drive shaft in one direction will be transmitted through one of said clutches to said first pair of driving members, and so that rotation of said drive shaft in the opposite direction will be transmitted through the other of said clutches to said second pair of driving members.

3. The combination set forth in claim 2 wherein the coupling elements of said first and second pairs of driving members are connectable with the coupling means of said winding drums in such a manner that one of the winding drums will be rotatable in one direction only by the coupling element of the first pair of driving members rotating in said one direction, and the other winding drum will be rotatable in the opposite direction only by the coupling element of the second pair of driving members rotating in said other direction, while the coupling element of the first pair of driving members which rotates in the other direction will be free to rotate idly relative to said one winding drum and the coupling element of said second pair of driving members which rotates in the opposite direction will be free to rotate idly relative to said second winding drum.

4. The combination of a film cartridge having a pair of rotatable film winding drums; and a reeling device cooperable with said winding drums so as to wind a length of film back and forth therebetween; said winding drums each having torque transmitting coupling means at its opposite ends, and said reeling device comprising, a reversibly rotatable drive shaft, first and second bevel gears axially aligned with said drive shaft for relative rotation independently thereof; a pair of one-way clutches operatively interposed between said drive shaft and said bevel gears so that rotation of said drive shaft in one direction will be transmitted to said first bevel gear through one of said clutches and so that rotation of said drive shaft in the opposite direction will be transmitted to said second bevel gear through the other of said clutches; a first pair of companion bevel gears in mesh with said first bevel gear; a first pair of drive members non-rotatably connected, respectively,

with said first pair of companion bevel gears; and each having a coupling element detachably connectable with said coupling means of said winding drum; and a second pair of drive members non-rotatably connected, respectively, with said second pair of companion bevel gears and each having a coupling element detachably connectable with said coupling means of said winding drums.

5. The combination set forth in claim 4 and further comprising brake means operatively associated with said one-way clutches so that rotation of said winding drums will be instantly arrested when transmission of torque thereto from said driving shaft is interrupted.

6. A reeling device for film winding drums comprising a reversibly rotatable drive shaft; a first pair of concentrically rotatable driving discs interconnected for relative rotation in opposite directions; radially outer and radially inner coupling elements secured, respectively, to said first pair of driving discs for rotation therewith; a second pair of concentrically rotatable driving discs interconnected for relative rotation in opposite directions; radially outer and radially inner coupling elements secured, respectively, to said second pair of driving discs; and a pair of one-way clutches operatively interposed between said drive shaft and said first and second pairs of driving discs so that rotation of said drive shaft in one direction will be transmitted through one of said clutches to said first pair of driving discs, and so that rotation of said drive shaft in the opposite direction will be transmitted through the other clutch to said second pair of driving discs.

7. A reeling device as set forth in claim 6, wherein said one-way clutches are of the wrap-around drag spring type.

8. A film cartridge comprising a casing and a pair of

film winding drums rotatably mounted in said casing in parallel transversely spaced relation to each other, each of said drums having at one of its axially opposite ends a central coupling hub and annular channel surrounding said hub; and at its other end, a central recess and a coupling flange surrounding said recess; the coupling hub and channel of one drum, and the central recess and coupling flange of the other drum facing one of the relatively opposite sides of said cartridge; and the central recess and coupling flange of said one drum, and the coupling hub and channel of said other drum facing the other of the relatively opposite cartridge sides.

9. A film cartridge as set forth in claim 8 wherein the coupling hub and the coupling flange of each winding drum have axial coupling pin receiving bores.

10. A film cartridge as set forth in claim 9 wherein axial bores of said coupling hub at one end of each of said winding drums are located in axially registering relation to said central recess at the other end thereof.

11. A film cartridge as set forth in claim 9 wherein axial bores of said coupling flange at one end of each of said winding drums are located in axially registering relation with said annular channel at the other end thereof.

12. A film cartridge as set forth in claim 9 wherein axial bores of said coupling hub at one end of each of said winding drums are located in axially registering relation with said central recess at the other end thereof; and wherein axial bores of said coupling flange at said other end of each of said winding drums are located in axially registering relation with said annular channel at said one end thereof.
